(57) **CLAIM**

The ornamental design for a gemstone and charm for a necklace or bracelet, as shown and described.

DESCRIPTION

FIG. 1 is a front view of a gemstone and charm for a necklace or bracelet showing my new design, using a first embodiment of the gemstone, a second through twenty-sixth embodiment of the charm could be substituted for the first embodiment of the gemstone;

FIG. 2 is a front view of the first embodiment of the gemstone for the gemstone and charm for a necklace or bracelet showing my new design;

FIG. 3 is a front view of a second embodiment of the gemstone for the gemstone and charm for a necklace or bracelet showing my new design;

FIG. 4 is a front view of a third embodiment of the gemstone for the gemstone and charm for a necklace or bracelet showing my new design;

FIG. 5 is a front view of a fourth embodiment of the gemstone for the gemstone and charm for a necklace or bracelet showing my new design;

FIG. 6 is a front view of a fifth embodiment of the gemstone for the gemstone and charm for a necklace or bracelet showing my new design;

FIG. 7 is a front view of a sixth embodiment of the gemstone for the gemstone and charm for a necklace or bracelet showing my new design;

FIG. 8 is a front view of a seventh embodiment of the gemstone for the gemstone and charm for a necklace or bracelet showing my new design;

FIG. 9 is a front view of an eighth embodiment of the gemstone for the gemstone and charm for a necklace or bracelet showing my new design;

FIG. 10 is a front view of a ninth embodiment of the gemstone for the gemstone and charm for a necklace or bracelet showing my new design;

FIG. 11 is a front view of a tenth embodiment of the gemstone for the gemstone and charm for a necklace or bracelet showing my new design;

FIG. 12 is a front view of an eleventh embodiment of the gemstone for the gemstone and charm for a necklace or bracelet showing my new design;

FIG. 13 is a front view of a twelfth embodiment of the gemstone for the gemstone and charm for a necklace or bracelet showing my new design;

(Continued)

FIG. 14 is a front view of a thirteenth embodiment of the gemstone for the gemstone and charm for a necklace or bracelet showing my new design;
 FIG. 15 is a front view of a fourteenth embodiment of the gemstone for the gemstone and charm for a necklace or bracelet showing my new design;
 FIG. 16 is a front view of a fifteenth embodiment of the gemstone for the gemstone and charm for a necklace or bracelet showing my new design;
 FIG. 17 is a front view of a sixteenth embodiment of the gemstone for the gemstone and charm for a necklace or bracelet showing my new design;
 FIG. 18 is a front view of a seventeenth embodiment of the gemstone for the gemstone and charm for a necklace or bracelet showing my new design;
 FIG. 19 is a front view of an eighteenth embodiment of the gemstone for the gemstone and charm for a necklace or bracelet showing my new design;
 FIG. 20 is a front view of a nineteenth embodiment of the gemstone for the gemstone and charm for a necklace or bracelet showing my new design;
 FIG. 21 is a front view of a twentieth embodiment of the gemstone for the gemstone and charm for a necklace or bracelet showing my new design;
 FIG. 22 is a front view of a twenty-first embodiment of the gemstone for the gemstone and charm for a necklace or bracelet showing my new design;
 FIG. 23 is a front view of a twenty-second embodiment of the gemstone for the gemstone and charm for a necklace or bracelet showing my new design;
 FIG. 24 is a front view of a twenty-third embodiment of the gemstone for the gemstone and charm for a necklace or bracelet showing my new design;
 FIG. 25 is a front view of a twenty-fourth embodiment of the gemstone for the gemstone and charm for a necklace or bracelet showing my new design;
 FIG. 26 is a front view of a twenty-fifth embodiment of the gemstone for the gemstone and charm for a necklace or bracelet showing my new design;
 FIG. 27 is a front view of a twenty-sixth embodiment of the gemstone for the gemstone and charm for a necklace or bracelet showing my new design;
 FIG. 28 is a back view of the first through twenty-sixth embodiments of the gemstone for the gemstone and charm for a necklace or bracelet showing my new design.
 FIG. 29 is a left side view of the first through twenty-sixth embodiments of the gemstone for the gemstone and charm for a necklace or bracelet showing my new design.
 FIG. 30 is a bottom view of the first through twenty-sixth embodiments of the gemstone for the gemstone and charm for a necklace or bracelet showing my new design.
 FIG. 31 is a right side view of the first through twenty-sixth embodiments of the gemstone for the gemstone and charm for a necklace or bracelet showing my new design.
 FIG. 32 is a perspective view of the charm for the gemstone and charm for a necklace or bracelet showing my new design.

FIG. 33 is a back view of the charm for the gemstone and charm for a necklace or bracelet showing my new design.
 FIG. 34 is a bottom view of the charm for the gemstone and charm for a necklace or bracelet showing my new design; and,
 FIG. 35 is a right side view of the charm for the gemstone and charm for a necklace or bracelet showing my new design.
 The broken lines shown in the drawings illustrate portions of the gemstone and charm for a necklace or bracelet that form no part of the claimed design.
